MINING MACHINE CUTTER BAR

Harry M. Morrow, Canton, Ohio, assignor to The
Bowdil Company

Application March 20, 1941, Serial No. 384,239

11 Claims. (Cl. 262—33)

My invention relates in general to cutter bars for mining machines and more particularly to fabricated cutter bars for mining machines.

An object of my invention is the provision of a fabricated cutter bar having removable parts which may be dis-assembled for repair or for replacement.

Another object of my invention is the provision of a removable arcuate end for the cutter bar.

Another object of my invention is the provision of a cutter bar having a removable chain guide channel construction, so that the angular wear strips may be easily and readily secured to the side of the chain guide channel construction.

Another object of my invention is the provision of a cutter bar of economical construction, in that a greater portion of the cutting bar is constructed of ordinary steel and in that a very minor portion of the bar is constructed of hard and expensive steel.

Another object of my invention is the provision of a cutting bar having a support channel construction in which is removably mounted a chain guide channel construction.

Other objects and a fuller understanding of my invention may be had by referring to the following description and claims, taken in conjunction with the accompanying drawing, in which:

Figure 1 represents a plan longitudinal view of a cutter bar embodying the features of my invention;

Figure 2 is a cross-sectional view of my cutter bar taken along the line 2—2 of Figure 1;

Figure 3 is a fragmentary cross-sectional view of my cutter bar taken along the line 3—3 of Figure 1;

Figure 4 is a fragmentary cross-sectional view of my cutter bar taken along the line 4—4 of Figure 1;

Figure 5 is a fragmentary cross-sectional view of my cutter bar taken along the line 5—5 of Figure 1;

Figure 6 is a fragmentary cross-sectional view of my cutter bar taken along the line 6—6 of Figure 1;

Figure 7 is a fragmentary and perspective view of an off-set substantially Z-shaped bar employed in the construction of my fabricated cutter bar;

Figure 8 is a perspective view of a nose member employed in the construction of my cutter bar;

Figure 9 is a perspective view of a semi-circular wear strip employed in the construction of my cutter bar;

Figure 10 is a perspective view of a semi-circular side plate and the semi-circular wear strip employed in the construction of my cutter bar, and

Figure 11 is a fragmentary cross-sectional view similar to the left-hand portion of Figure 2 but showing a modification thereof.

With reference to the drawing, my fabricated cutter bar comprises two main portions; namely, a longitudinal portion represented generally by the reference character 15 and an arcuate end portion represented generally by the reference character 16. Around the outer edges of the longitudinal portion 15 and the arcuate end portion 16 is a chain guide channel 18 in which revolves the mining machine chain utilized for cutting coal and other substances. In Figure 1 of the drawing, the bottom of the chain guide channel 18 is designated by the reference character 28.

As illustrated, the longitudinal portion 15 comprises two spaced longitudinal side portions 17 of substantially identical construction. Each of the spaced longitudinal side portions 17 comprise generally two substantially rectangular bars 19 and two off-set substantially Z-shaped bars 20 having a base flange 21 forming an outside off-set portion 22 and a guide flange 23 forming an inside off-set portion 24, see Figures 1, 2 and 7. The base flanges 21 of the off-set substantially Z-shaped bars are secured together and hold the guide flanges 23 apart with the inside off-set portions 24 forming the guide channel for the two spaced longitudinal side portions 17 of the cutter bar. The rectangular bars 19 are disposed on opposite sides of the base flanges 21 and engage the outside off-set portions 22 of the base flanges 21. As shown in Figure 2, the rectangular bars 19 and the base flanges 21 have registering openings extending therethrough and receive a bolt 25 which secures the off-set substantially Z-shaped bars 20 and the rectangular bars 19 together. The registering openings and the bolt 25 may be spaced along each of the longitudinal side portions 17 of the cutter bar at suitable spaced intervals to give strength and rigidity to the cutter bar. As illustrated in Figure 2, angular wear strips 26 are secured to the inside edges of the guide flanges 23 forming the chain guide channel 18 and extend over and against the outer edges thereof in order to provide wearing surfaces not only on the inside of the chain guide channel 18 but also along the outer edges thereof. The angular wear strips 26 may be secured to the inside surfaces of the

chain guide channel 18 by means of spaced rivets 27.

As illustrated in Figures 1 and 3, the inside edges of the rectangular bars 19 may be bridged or tied together by means of a bridging block 32 which may be welded at 33 or otherwise suitably connected to the inside edges of the rectangular bars 19. The combination of the bridging block 32 and the arcuate end portion 16 function to secure the two spaced longitudinal side portions 17 in substantially parallel alignment. The inside edges of the rectangular bars 19 are reenforced with respect to each other by means of reenforcing spacer blocks 34 placed at suitable intervals along the inside edge of the rectangular bars, see Figures 1 and 6. The reenforcing spacer blocks 34 may be welded at 35 or otherwise suitably connected to the inside edges of the rectangular bars 19.

In actual practice, the left-hand end of the cutter bar is adapted to be mounted upon a mining machine which has a power driven chain sprocket wheel for forceably driving the cutter chain around the chain guide channel 18. The mounting construction at the left-hand end of the cutter bar depends upon the design of each particular mining machine and all of them are not alike. The mounting, as illustrated in Figures 1 and 5, comprises a mounting tie plate 36 welded or otherwise suitably connected to the bottom side of the cutter bar. The welded connection of the mounting tie plate 36 to the cutter bar may be at 37 and 38 or at any other suitable location. As viewed from the top side of the cutter bar as shown in Figures 1 and 5, the rectangular bars 19 are cut away at 39 to provide an enlarged opening for the mounting of the cutter bar to the mining machine.

The arcuate end portion 16 comprises generally two semi-circular side plates 43, an intermediate nose member 44, and a semi-circular wear strip 52 all secured together and connected to the right-hand end of the assembled rectangular bars 19 of the spaced longitudinal side portions 17. As illustrated in Figures 1, 2 and 8, the intermediate nose member 44 comprises a semi-circular end 45 and an anchoring portion 46. The anchoring portion 46 of the intermediate nose member 44 lies between the spaced rectangular bars 19 at the right-hand end of the longitudinal side portions 17 and is arranged to be securely mounted thereto by welding or any other suitable means. As shown in Figure 2, the weld to securely mount the anchoring portion 46 to the rectangular bars 19 may be at 47 or any other suitable place. The opposite sides of the intermediate nose member 44 may be reenforced by means of reenforcing members 48. The right-hand end of the reenforcing member 48 is round as indicated by the reference character 49 and is arranged to fit complementarily within a round recess 50 in each of the side plates 43. The width of the reenforcing members 48 are such as to fit between the inside edges of the spaced rectangular bars 19 of the longitudinal side portions 17. The reenforcing members 48 may be welded or otherwise suitably connected to the rectangular bars 19. The weld may be at 51 or at any other suitable place. Instead of welding the anchoring portion 46 and the reenforcing members 48 in separately to the rectangular bars 19, the reenforcing member 48 may be first welded or otherwise suitably connected to opposite sides of the intermediate nose member 44, after which the intermediate nose

member 44 and the reenforcing members 48 may be welded to the rectangular bars 19 as a unit. As shown in Figures 4, 9 and 10, the inside surfaces of the semi-circular side plates 43 are provided with a tongue 54 which is adapted to receive a groove 53 on opposite sides of the semi-circular wear strip 52. In mounting the arcuate end portion 16 to the right-hand end of the longitudinal side portions 17 of the cutter bar, the semi-circular wear strip 52 is first positioned between the semi-circular side plates 43, after which the side plates 43 are bolted to the semi-circular end 45 of the intermediate nose member 44 by bolts 51 or by any other suitable means. The inside edge of the semi-circular wear strip 52 bears against the semi-circular end 45 of the intermediate nose member 44. As shown in Figures 4 and 10, the inside surfaces of the semi-circular side plates 43 are cut away so as to provide inward projection 55 near the outer peripheral edges thereof. The cross-section of the inward projection 55 coincides substantially with the angular wear strips 76, so that the chain guide channel 18 is substantially uniform throughout its entire length. The semi-circular side plates 43 are constructed of wear resistant material which means also that the inward projection 55 is of wear resistant material. The angular wear strips 76 are also constructed of wear resistant material, but all of the remaining parts of the cutter bar are constructed of ordinary steel. Therefore, my cutter bar represents an economical design from the standpoint of cost since a very small amount of the steel is wear resistant material which is many times more expensive than the ordinary steel used in the remaining parts of the cutter bar.

In actual operation, the riveting of the wear resistant strips to the inside surfaces of the chain guide channel of a solid cutter bar such as shown in Patent No. 1,930,466 issued to N. K. Bowman on October 17, 1933, evolved a great deal of difficulty. The riveting operation was rather difficult for the reason that the ends of the rivets in the chain guide channel in a solid bar were not accessible for efficient riveting action. Attempts were made to employ a wedge to hold the rivets in tight against the wear resistant strips while the outer ends of the rivets were upset but the results obtained were not satisfactory. In my invention the wear resistant strips 26 may be riveted to the off-set substantially Z-shaped bars 20 before assembling the cutter bar in the factory. In the event that it becomes necessary to replace or repair the wear resistant strips 26 in the field, the off-set substantially Z-shaped bars 20 may be readily removed or dis-assembled from the cutter bar by removing the bolts 25. Upon the dis-assembly of the off-set substantially Z-shaped bars 20, the rectangular bars 19 form what might be characterized as a support channel. In other words, each of the longitudinal side portions 17 of my cutter bar is of a construction having a double channel in which the inner channel formed by the two spaced rectangular bars 19 constitutes a support channel construction and in which the channel formed by the two off-set substantially Z-shaped bars 20 form the chain guide channel around which the cutter chain of the mining machine revolve. The outer chain guide channel construction is removably mounted in the inner support channel construction to facilitate repairs and the replacement of parts.

The construction of my cutter bar also readily affords a simple arrangement for varying the

thickness of the cutter bar to accommodate mining machine chains of different sizes and widths. Thus, in Figure 11, I illustrate a thicker cutter bar by employing a spacer 56 between the base flanges 21 of the off-set substantially Z-shaped bars 20. The arcuate end portion 16 of the cutter bar may likewise be made wider by using suitable spacers in order to make the arcuate end portion 16 of the cutter bar to lie in substantially the same plane as the plane of the two longitudinal side portions 17 of the cutter bar.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A cutter bar for a mining machine comprising, in combination, two spaced longitudinal side portions and an arcuate end portion having a guide channel provided around their outer edges, each of said longitudinal side portions being similarly constructed and comprising two substantially rectangular bars and two off-set substantially Z-shaped bars having a base flange forming an outside off-set portion and a guide flange forming an inside off-set portion, said base flanges being secured together and holding the guide flanges apart with the inside off-set portions forming the guide channel for the two spaced longitudinal side portions of the cutter bar, angular wear strips secured to the inside edges of the guide flanges forming the said guide channel and extending over and against the outer edges thereof, said rectangular bars being disposed on opposite sides of the base flanges and engaging the outside off-set portions of the base flanges, said rectangular bars and said base flanges having registering openings extending therethrough, fastening means extending through the registering openings for securing the off-set substantially Z-shaped bars and the rectangular bar together, means at spaced longitudinal intervals for securing the rectangular bars together, said arcuate end portion of the cutter bar comprising two substantially semi-circular side plates of wear resistant material, an intermediate nose member having a substantially semi-circular end and a substantially semi-circular wear strip all secured together, said nose member being secured to one end of the assembled rectangular bars with the semi-circular end extending longitudinally therefrom, means for securing the side plates on opposite sides of the extended semi-circular end of the nose member to form sides for the guide channel around the said arcuate end portion of the cutter bar, the inside surfaces of the side plates at the peripheral edge thereof having an inward projection coinciding substantially with the wear strips secured to the said guide flanges of the off-set substantially Z-shaped bars, and means for securing the semi-circular wear strip in the bottom of the guide channel around the said arcuate end portion of the cutter bar.

2. A cutter bar for a mining machine comprising, in combination, two spaced longitudinal side portions and an arcuate end portion having a guide channel provided around their outer edges, each of said longitudinal side portions being similarly constructed and comprising two substantially rectangular bars and two off-set substantially Z-shaped bars having a base flange

5 forming an outside off-set portion and a guide flange forming an inside off-set portion, said base flanges being secured together and holding the guide flanges apart with the inside off-set portions forming the guide channel for the two spaced longitudinal side portions of the cutter bar, angular wear strips secured to the inside edges of the guide flanges forming the said guide channel and extending over and against the outer edges thereof, said rectangular bars being disposed on opposite sides of the base flanges and engaging the outside off-set portions of the base flanges, said rectangular bars and said base flanges having registering openings extending therethrough, fastening means extending through the registering openings for securing the off-set substantially Z-shaped bars and the rectangular bar together, means at spaced longitudinal intervals for securing the rectangular bars together, and means for securing the said arcuate end portion of the cutter bar to one end of the assembled rectangular bars.

3. A cutter bar for a mining machine comprising, in combination, two spaced longitudinal side portions and an arcuate end portion having a guide channel provided around their outer edges, each of said longitudinal side portions being similarly constructed and comprising two substantially rectangular bars and two off-set substantially Z-shaped bars having a base flange forming an outside off-set portion and a guide flange forming an inside off-set portion, said base flanges being secured together and holding the guide flanges apart with the inside off-set portions forming the guide channel for the two spaced longitudinal side portions of the cutter bar, said rectangular bars being disposed on opposite sides of the base flanges and engaging the outside off-set portions of the base flanges, said rectangular bars and said base flanges having registering openings extending therethrough, fastening means extending through the registering openings for securing the off-set substantially Z-shaped bars and the rectangular bar together, means at spaced longitudinal intervals for securing the rectangular bars together, and means for securing the said arcuate end portion of the cutter bar to one end of the assembled rectangular bars.

4. A cutter bar for a mining machine comprising, in combination, two spaced longitudinal side portions and an arcuate end portion having a guide channel provided around their outer edges, angular wear strips secured to the inside edges of the guide channel in the longitudinal side portions and extending over and against the outer edges thereof, said arcuate end portion of the cutter bar comprising two substantially semi-circular side plates of wear resistant material, an intermediate nose member having a substantially semi-circular end and a substantially semi-circular wear strip all secured together, said nose member being secured to one end of the two spaced longitudinal side portions with the semi-circular end extending longitudinally therefrom, means for securing the side plates on opposite sides of the extended semi-circular end of the nose member to form sides for the guide channel around the said arcuate end portion of the cutter bar, and means for securing the semi-circular wear strip in the bottom of the guide channel around the arcuate end portion of the cutter bar, the inside surfaces of the side plates at the peripheral edge thereof having an inward projection coinciding substantially with the wear strips secured to the inside edges of the guide

channel in the longitudinal side portions of the cutter bar.

5. A cutter bar for a mining machine comprising, in combination, two spaced longitudinal side portions and an arcuate end portion having a guide channel provided around their outer edges, said arcuate end portion of the cutter bar comprising two substantially semi-circular side plates of wear resistant material, an intermediate nose member having a substantially semi-circular end and a substantially semi-circular wear strip all secured together, said nose member being secured to one end of the two spaced longitudinal side portions with the semi-circular end extending longitudinally therefrom, means for securing the side plates on opposite sides of the extended semi-circular end of the nose member to form sides for the guide channel around the said arcuate end portion of the cutter bar, and interfitting tongue-and-groove means on the side plates and the semi-circular wear strip for securing the semi-circular wear strip in the bottom of the guide channel around the arcuate end portion of the cutter bar.

6. A cutter bar for a mining machine comprising, in combination, a longitudinal portion and an arcuate end portion having a chain guide channel provided around their outer edges, said longitudinal portion comprising a longitudinal structure having a longitudinal support channel along opposite longitudinal sides thereof and two off-set substantially Z-shaped bars secured in each of the longitudinal support channels, each of said off-set substantially Z-shaped bars having a base flange forming an outside off-set portion and a guide flange forming an inside off-set portion, means extending through the support channels and the base flanges therein for removably securing the base flanges of two off-set substantially Z-shaped bars within each of the support channels with the said outside off-set portion engaging the inside surfaces of the support channel and holding the said guide flanges apart with the said inside off-set portions forming the chain guide channel for the longitudinal portion of the cutter bar.

7. A cutter bar for a mining machine comprising, in combination, a longitudinal portion and an arcuate end portion having a chain guide channel provided around their outer edges, said longitudinal portion comprising longitudinal support channel means, chain guide channel means removably mounted therein to form the chain guide channel along the longitudinal portion of the cutter bar, and means extending transversely through the support channel means and the chain guide channel means for securing the chain guide channel means in the support channel means.

8. A cutter bar for a mining machine comprising, in combination, a longitudinal portion and an arcuate end portion having a chain guide channel provided around their outer edges, said longitudinal portion comprising two longitudinal sides of substantially identical construction, each of said sides having an inner support channel construction, an outer chain guide channel construction removably mounted in the inner support channel construction, and means extending transversely through the support channel construction and the chain guide channel construction for securing the chain guide channel construction in the support channel construction.

15. 9. A cutter bar for a mining machine comprising, in combination, a longitudinal portion and an arcuate end portion having a chain guide channel provided around their outer edges, said longitudinal portion comprising two longitudinal sides of substantially identical construction, each of said sides having an inner support channel construction, an outer chain guide channel construction removably mounted in the inner support channel construction, said outer chain guide channel construction comprising two offset substantially Z-shaped bars, and means extending transversely through the support channel construction and the chain guide channel construction for securing the chain guide channel construction in the support channel construction.

20. 10. A cutter bar for a mining machine comprising, in combination, a longitudinal portion and an arcuate end portion having a chain guide channel provided around their outer edges, said longitudinal portion comprising two longitudinal sides of substantially identical construction, each of said sides having an inner support channel construction, an outer chain guide channel construction removably mounted in the inner support channel construction, said outer chain guide channel construction comprising two off-set substantially Z-shaped bars, and means extending transversely through the inner support means and the chain guide channel construction for securing the chain guide channel construction in the inner support means.

25. 11. A cutter bar for a mining machine comprising, in combination, a longitudinal portion and an arcuate end portion having a chain guide channel provided around their outer edges, said longitudinal portion comprising longitudinal support channel means, chain guide channel means mounted therein to form the chain guide channel along the longitudinal portion of the cutter bar, and means extending transversely through the support channel means and the chain guide channel means for securing the chain guide channel means in the support channel means.

HARRY M. MORROW.
